DESIGN FOR A FISH LURE

James E. Clark, St. Petersburg, Fla.

Application July 17, 1940, Serial No. 93,723

Term of patent 14 years

To all whom it may concern:

Be it known that I, James E. Clark, a citizen of the United States and a resident of St. Petersburg, in the county of Pinellas and State of Florida, have invented a new, original, and ornamental Design for a Fish Lure, of which the following is a specification, reference is had to the accompanying drawing forming part thereof, in which:

Figure 1 is a front perspective view of a fish lure, showing my new design.

Figure 2 is a rear perspective view thereof.

Figure 3 is a rear elevation.

Figure 4 is a side elevation.

I claim:

The ornamental design for a fish lure, as shown.

JAMES E. CLARK.
